DEVICE FOR STRETCHING THE THROAT
OF SHOE VAMPS

John B. Nicoletti, Chicago, Ill.

Application June 6, 1935, Serial No. 25,274

4 Claims. (Cl. 12—103)

This invention relates to a device for stretching the throat of a shoe vamp.

In the manufacture of shoes, and particularly ladies' pumps, shaping the vamp and its throat 5 presents a difficult problem. It is essential in a comfortably fitting pump or shoe that the vamp should readily adapt itself to the shape of the instep without binding and exerting pressure thereagainst. However, the shape and 10 location of the instep varies with different individuals. It is impossible, therefore, to standardize the shape or design of the throat of the vamp, but to adapt the same to each instep at the time the shoes are fitted if comfort and 15 appearance are desirable. I am aware that attempts have been made heretofore to adjust the throat of a shoe vamp to an instep by devices which would spread the material by a rolling operation. These devices are highly unsatisfactory in actual use because they readily break 20 the binding along the edge of the vamp and invariably break the fibre of the leather which destroys the appearance of the shoe. The rolling action of such prior art devices merely flattens 25 the material, and consequently causes the throat to lose its conforming appearance at the instep.

A further object of the present invention is to provide a device of this type adapted to accomplish its ends by fitting to and stretching the 30 throat of a shoe vamp and simultaneously to conform the throat during the stretching operation to the shape of the instep so that the vamp will retain its conforming appearance and the 35 binding will be protected against being broken or destroyed.

A principal object of the present invention is to provide, therefore, an improved type of device capable of comfortably adapting the throat 40 of a vamp to an instep without destroying the appearance of the shoe or without breaking the fibre or the binding along the edges.

A still further object of the invention is to provide a device of this type capable of easy and 45 ready use and which may be employed to accomplish its purpose without destroying the appearance of the shoe.

A still further object of the invention is to 50 construct a simple form of device of this type so that its operation is simple and so that it may be readily used for various other purposes in the comfortable fitting of a shoe to the foot.

Other objects and advantages of the invention 55 will be apparent from the detailed description

taken in connection with the accompanying drawing which forms a part hereof.

In the drawing:

Figure 1 is a perspective view of a device embodying the invention as applied in use to a ladies' 5 pump;

Fig. 2 is an enlarged view looking downwardly at the forward end of the device, the rear end of the handles being omitted;

Fig. 3 is a view of the forward end of the device, a portion of which is in section to illustrate the manner in which it grips the throat of a shoe vamp to stretch and simultaneously to conform the same to a desired shape;

Fig. 4 illustrates the vamp of this shoe before 15 the device is applied;

Fig. 5 illustrates the same vamp after the throat thereof has been stretched; and

Fig. 6 is an enlarged detail view illustrating the head of the lower clamping member in elevation and the head of the upper clamping member partly in section to show the relation of these parts.

The device illustrated in the drawing as one embodiment of the invention comprises a pair of 25 clamping members 2 and 3 having rearwardly extending handle portions 4 and 5 and forwardly extending jaws 6 and 7. Clamping members 2 and 3 may be suitably pivoted together by means of a pintle 8.

Lower jaw 7 is a continuation of upper handle 5 and has its forward end formed into an enlarged head 8. Upper jaw 6 is a continuation of lower handle 4 and is fitted with a head end 9 having an opening 10 of substantially the same 35 contour as head 8 so as to receive the same in cooperating relation when clamping members 2 and 3 are brought together. Head 8 is cut away at 11 to form a seat 12 and a stop in the form of an abutment wall 13. As shown in Fig. 2, 40 outer face 14 of head 8 is curved at the corners 19 and 20 and across the central part to conform to the shape of wall 15 of opening 10. However, head 8 may be slightly smaller than opening 10 so that a predetermined space 16 may be provided between wall 14 and wall 15. This predetermined space may represent substantially the same or different thickness of the leather or other material comprising the throat of the vamp.

The width of head 8, as well as its shape in this dimension, is determined by the part of the shoe to which it is to be adapted. In case the device is applied to the throat of a ladies' pump, head 8 may be of the same width and shape as the throat 55

of the vamp so that after the stretching operation the throat will be formed to the instep and not merely flattened to destroy the appearance of the pump.

5 When the device is mounted in position upon the pump, jaws 6 and 7 will be opened slightly to separate head 8 from head 9. The throat of the shoe vamp may then be brought against shoulder 13 and rested upon seat 12. Inasmuch as seat 12 and shoulder 13 are approximately the same shape crosswise as the throat of the vamp, the shoulder 13 serves as a positioning means for the throat of the vamp to prevent the latter from being improperly positioned upon seat 12. In other words, 15 retaining wall 13 acts to position the throat upon seat 12 due to its shape and relation with seat 12. Consequently, the throat will be placed upon seat 12 in proper position with respect to the front of the pump so that at all times when head 9 is brought down upon head 8, the proper stretching of the throat is effected without destroying the appearance of the pump.

It will be noted in Fig. 3 that after the throat of the pump is placed upon seat 12 and against abutment wall 13 which acts as a limit in the seating of the throat upon seat 12, applying pressure between heads 8 and 9 forces the inner edge 18 of head 9 against the vamp which causes the edge of the throat to pull away slightly from abutment wall 13. However, the throat of the vamp is also securely held at corners 19 and 20, which are curved to conform to the shape of the curved throat, and which, therefore, function to retain this throat securely between edge 19 and the wall 35 of seat 12.

It may be desirable to keep the device in this relation upon the throat of the vamp for a predetermined period in order that the throat will receive a fixed or set stretch, as indicated at 21 40 in Fig. 5. To this end it is suggested that a threaded bolt 22 may be anchored near the outer end of lower handle 4 and passed through an elongated slot 23 in handle 5. A wing nut 24 may be employed to apply the proper pressure between 45 these handles in order to effect the permanent stretch 21, as shown in Fig. 5, in the throat of the vamp.

It will be apparent from the foregoing description that I have provided a clamping device comprising clamping jaws having inner engaging edges or surfaces which are adapted to receive the throat of a shoe vamp and grip the same while applying pressure thereto in order to stretch the material and thereby conform it to a shape which 55 adapts it to insteps of different heights or shapes. The extent of the stretching of the material depends, of course, upon the pressure applied and the length of time the device remains clamped upon the throat of the vamp. Moreover, the size 60 of seat 12 also determines the amount of stretch, it being noted that this may be varied considerably in the making of the device so as to secure greater or lesser stretching of the throat of the vamp, if desired. Moreover, it will be noted that the de-

vice herein disclosed does not tend to break the binding 25 about the edge of the shoe because the stretching action is effected beyond this binding.

Moreover, it will be noted from the foregoing 5 description that the device disclosed herein is extremely simple in construction and operation and assures a proper application to the shoe due to its shape and relation of parts. Accordingly, the same principle of operation may be applied 10 in a device of slightly different shape so as to adapt it to the stretching of the shoe at different locations, if so desired.

Without further elaboration, the foregoing will 15 so fully explain the gist of my invention that others may, by applying current knowledge, readily adopt the same for use under varying conditions of service, without eliminating certain features, which may properly be said to constitute the essential items of novelty involved, which 20 items are intended to be defined and secured to me by the following claims.

I claim:

1. In a device of the class described, a pair of members movable relative to each other, and 25 clamping jaws on said members, one of said jaws being apertured to receive the other jaw in clamping relation, the other jaw having a seat formed thereon for receiving the throat of a shoe vamp, and means for limiting the positioning of 30 the vamp upon said seat to prevent the edge of the vamp from being gripped by said jaws whereby said jaws are brought together in clamping relation to stretch or preform the throat of said shoe vamp. 35

2. In a device of the class described, a pair of members movable relative to each other, and 40 clamping jaws on said movable members, one end of one of said jaws having a seat for receiving the throat of a shoe vamp, there being means for positioning the throat upon said seat, the corresponding end of the other jaw having an edge 45 cooperating with said seat to grip the throat thereupon and preform it to correspond to the shape of an instep. 50

3. In a device of the class described, a pair of members movable relative to each other, and 55 clamping jaws on said movable members, one of said jaws having a cut-away portion forming a seat and adjoining shoulders for receiving the 60 throat of a vamp in a predetermined position, the other jaw having a cooperating portion for gripping the throat of the vamp upon said seat.

4. In a device of the class described, a pair of members movable relative to each other, and 65 clamping jaws on said movable members having 70 cooperating engaging portions for receiving and stretching the throat of a vamp, one of said portions having a seat and a shoulder for positioning the throat upon said seat, the other portion being apertured to receive the first portion, and means for applying a pressure between said portions. 80

JOHN B. NICOLETTI.
